(57) **CLAIM**

The ornamental design for a container for breeding small animals, as shown and described.

DESCRIPTION

FIG. 1 is a perspective view of our design for a container for breeding small animals;

FIG. 2 is a front elevational view thereof;

FIG. 3 is a rear elevational view thereof;

FIG. 4 is a top view thereof;

FIG. 5 is a bottom plan view thereof;

FIG. 6 is a left-side elevational view thereof;

FIG. 7 is a right-side elevational view thereof; and,

FIG. 8 is an exploded perspective view thereof.
